AIRPORT FUELING APPARATUS

Roger J. Daley, John J. Gosney, and Winfield N. Neiman, Fort Wayne, Ind., assignors to The Wayne Pump Company, Fort Wayne, Ind., a corporation of Maryland

Application March 30, 1951, Serial No. 218,414

10 Claims. (Cl. 222—23)

1

This invention relates to a new and improved liquid dispensing system and more particularly to such a system especially adapted for fueling planes at airports.

Airplane fueling requires that fuel be supplied in large quantities at relatively high discharge rates to minimize the time for fueling planes. It is also important to provide means for removing fuel from planes which is required at times for trimming plane tanks properly or for permitting greater cargo loading within prescribed over-all weight limits for a plane. Systems have been developed heretofore which involve the use of a dry hose for fuel delivery. Such a dry hose system is important where comparatively large hoses are used to allow rapid supply of fuel. In airplane fueling, hoses are of substantial length and a large hose filled with gasoline is heavy and difficult to handle. A difficulty presented with the use of large and long hoses under the dry hose system is the fact that such a hose becomes dangerous when suddenly filled with gasoline under substantial pressures. Such a hose may also have a capacity of a large quantity of gasoline and it is important to provide accurate metering of the gasoline actually delivered to the plane. It is therefore important that the apparatus be designed to meter the actual delivery from the nozzle and not the gas used to fill the dry hose.

It is an object of the present invention to provide a new and improved liquid dispensing apparatus of the dry hose type.

It is a further object to provide such a system adapted to fill the dry hose at a lower pressure and dispense liquid at a higher pressure.

It is also an object to provide a system of this character in which the lower pressure hose fill and higher pressure dispensing operations are normally automatically controlled and in which such operations may be manually controlled if desired.

It is an additional object to provide a system having a meter and counter which are not operated during the hose filling operation, but are operated during the higher pressure dispensing operation.

It is another object to provide that such meter operation is automatically controlled.

It is a further object to provide such a meter and counter associated with the dispensing apparatus in such manner that the meter is normally not operated when draining the hose, but which may be operated if desired when defueling a plane or the like.

2

It is also an object to provide a system including electronic controls which may be in part manually operated and in part operated by fluid pressure.

5 It is an additional object to provide a system in which such electronic control may be in part operated by fluid pressure at or adjacent the discharge nozzle of the hose.

It is a further object to provide dispensing apparatus of this type in which variation of pressures to the delivery hose is accomplished independently of the pressure pump.

It is also an object to provide a construction in which a portion of the fluid flow from the 15 pump may be by-passed back to the source of supply in order to modify flow and pressure in the hose.

It is an additional object to provide a control system which, in the event of control failure, will 20 automatically restore the apparatus to safe condition with an empty hose.

It is another object to provide liquid dispensing apparatus designed for commercial production and use.

25 Other and further objects will appear as the description proceeds.

Certain preferred embodiments of our invention have been shown in the accompanying drawings in which—

30 Figure 1 is a somewhat diagrammatic showing, partly in section, of the apparatus, the parts being in position for the evacuation operation or suction from the dispensing hose;

Figure 2 is a view similar to Figure 1 showing the parts in the position for slow or low pressure fill of the hose;

Figure 3 is a view similar to Figure 1 showing the parts in position for high pressure dispensing through the hose;

40 Figure 4 is a fragmentary cross-section, on an enlarged scale, of the solenoids and slide valves with the parts in position for slow fill;

Figure 5 is a diagrammatic showing of the electronic control circuit;

45 Figure 6 is an elevation of the hose nozzle and switch assembly;

Figure 7 is an enlarged view, partly in section, of the switch assembly of Figure 6;

Figure 8 is a plan view of the switch assembly with the cover removed;

Figure 9 is a transverse section through the switch and hose assembly shown in Figures 7 and 8; and

50 Figure 10 is an enlarged view, partly in section, of the pressure switch.

Referring first to Figures 1, 2 and 3, the apparatus includes a high lift rotary pump 22 which may be of any suitable construction. The details of this pump form no part of the present invention and will not be shown or described in detail. The suction inlet passage 24 is connected to the flange 25 at the inlet side of pump 22. This inlet passage 24 communicates through an opening normally closed by the inlet valve 27 carried on stem 28, with an entrance passage 29 in communication with a pipe 30. This pipe 30 leads to any suitable tank or other container for the gasoline or other liquid to be dispensed.

The inlet passage 24 communicates with the by-pass passage 32 which leads through check valve 34 and pipe 35 to the valve chamber 37. Evacuation valve 39 is adapted to be seated to close the valve passage 40 leading from valve chamber 37 to the common chamber 41. The discharge valve 43 normally closes a valve opening 45 between the common chamber 41 and the discharge passage 47 leading from the pump 22. A passage 49 connects the pump discharge passage 47 to pipe 51 which leads to chamber 53 above the return valve 54. This return valve 54 is carried on stem 55 guided in spider 58 which stem is aligned with stem 28 of the inlet valve 27. The return passage 56 connects the port controlled by valve 54 to passage 57 which leads to the entrance chamber 29.

A perforated control line 59 extends across the discharge passage 47 and is connected by passage 61 to a cross passage 63 in the slide valve housing 64 above which is located the solenoid housing 65. A control passage 66 leads from the valve chamber 37 to a control chamber 68 located in the lower part of the slide valve housing 64. This control passage 66 is provided at its upper end with a ball check valve 71 which permits passage of fluid only from the control chamber 68 to the control passage 66.

The dispensing passage 73 leads from common chamber 41 to the meter 75. This meter is connected to a counter or indicator 77 by means of a clutch, not shown, so that the counter may be put in and out of operation as desired. The outlet 79 of meter 75 is connected through hose 81 to the switch housing 83 and dispensing nozzle 85. The grounding portion 86 of the control wire 163 is connected to nozzle 85 and provided with plug 87 for connection to the plane being serviced.

The inlet valve 27 is carried by stem 28 and this stem passes through an intermediate valve actuating chamber 88 and carries a piston 89 in that chamber. That portion of stem 28 extending above chamber 88 is adapted in the upper position of the piston 89 to engage the underface of valve 54 and hold that valve closed. That portion of chamber 88 above the piston 89 is connected by passage 91 to passage 93 which leads into the slide valve housing 64 adjacent the right hand slide valve 95. The lower portion of chamber 88 below the piston 89 is connected by passage 97 to an upper passage 99 also extending into the slide valve housing 64 adjacent the slide valve 95.

The passage 93 leading from slide valve housing 64 in addition to being connected to passage 91 is connected to passage 101, which passage leads into the upper portion of chamber 103 above the piston 105. This piston 105 is carried upon the upper end of the stem 107 which carries the discharge valve 43. The lower portion of chamber 103 below piston 105 is connected

by passage 109 with passage 99 leading into the slide valve housing 64. It will be noted that a spring 111 is placed about valve stem 107, this spring engaging the upper face of discharge valve 43 and normally holding that valve in closed position upon its seat.

The evacuation valve 39 is carried on stem 113 which extends into chamber 115 where the stem carries the piston 117. The lower part of chamber 115 below piston 117 is connected by passage 119 with the slide valve housing 64 and communicates with the left hand slide valve 121. Similarly, the upper portion of chamber 115 above piston 117 is connected by passage 123 with the upper portion of slide valve 121. The chambers 125 and 126 are located above the slide valves 95 and 121, respectively, and these chambers are connected by passages 128 and 129, respectively, with the cross passage 63 in the slide valve assembly block 64. The slide valves 95 and 121 are urged upwardly by the springs 131 and 133 located below the slide valves. The passage 135 leads from the chamber 126 to valve 136 and the similar passage 138 leads from chamber 125 to the valve 139. The valves 136 and 139 are both connected to the pipe 141 which connects down to the by-pass passage 32.

The solenoids 145 and 147 are carried in housing 155 and are adapted to operate plungers 148 and 150, respectively. These plungers normally rest on the associated slide valves 95 and 121, which valves are normally held in the lower position against the action of springs 131 and 133 by the fluid pressure in the system. The solenoids 145 and 147 are connected by wires 153 and 154, respectively, to the electronic control panel within the housing 157 and both are connected to this control panel by the common wire 155. The electronic control panel within housing 157 is also connected by wires 159 and 160 to a clutch operating solenoid carried in housing 161 on the counter assembly 77. The electronic control panel in housing 157 is further connected by wire 163 which leads to a switch mounted in housing 384 mounted on the counter or indicator housing 77, leading through hose 81 to the hose switch assembly in housing 83.

In Figure 4, the solenoid and slide valve construction is shown on an enlarged scale, the view being from the reverse side to the somewhat diagrammatic showing of Figures 1, 2 and 3. The slide valve housing 64 is provided with a pair of vertically extending cylindrical openings 201 and 203 and in these openings are located the ported sleeves 205 and 207. The slide valves 95 and 121 move freely in the sleeves 205 and 207. The solenoids 145 and 147 are in the housing 65 and are fitted about the tubular members 209 and 210 which, as shown, have closed upper ends. The plungers 148 and 150 move freely in the axial openings in the sleeves 209 and 210. The two plungers 148 and 150 are similar and, as shown in connection with plunger 150, are provided with internal bores 212. They are also provided with reduced lower sections 214 and 215 in which fit the movable valve members 217 and 218. These latter members are provided with elongated slots 220 and 221 fitted about cross pins 223 and 224 which pins are fixedly secured in the reduced lower portions 214 and 215 of the plungers 148 and 150. The valve members 217 and 218 are thus permitted a limited movement relative to the plungers 148 and 150. The slide valves 95 and 121 are provided with internal bores 75 226 and 227 with reduced upper portions 229

and 230 which are adapted to be closed by the valve members 211 and 218 when those members are in their lower position.

When the solenoids 145 and 147 are not energized the plungers 148 and 150 are in their lower position, sealing ports 229 and 230. Closing these ports puts chambers 125 and 126 under pressure when the pump is operated and this pressure forces the slide valves into their lower position compressing springs 131 and 133 as shown in connection with spring 133 and slide valve 121 at the right of Figure 4. In this position the shoulder 232 of the sleeve valve 121 rests on the upper portion 234 of the ported fixed sleeve 207.

The solenoid 145 at the left of Figure 4 is shown as energized. It has drawn the plunger 148 to its uppermost position and the valve member 211 has been carried up by the pin 223. The port 229 in the sleeve valve 95 is thus opened, equalizing the pressure on both sides of the slide valve 95 and as aided by spring 131 raises it to its uppermost position.

The cross section shown in Figure 4 does not include all of the passages communicating with the ported sleeves 205 and 207, as these passages enter in different planes. However, the relative positions and functioning of these passages are fully shown diagrammatically in Figures 1 to 3, inclusive.

The valve and nozzle assembly is shown in Figures 7 to 10, inclusive, together with the control switch arrangement. The hose 81 carries the switch housing 83, the switches being contained in an upwardly projecting chamber 240, shown in longitudinal section in Figure 7 and in cross section in Figure 9. The nozzle 85 is shown in Figure 6 as connected directly to the switch housing 83, the nozzle containing the usual type of manual control valve (not shown) actuated by plunger 242 and hand lever 244. The grounding portion 86 of the control wire 163 is shown as connected with the nozzle structure and is provided at its free end with the plug 87 for connection to the plane being serviced.

The switch chamber 240 contains a U-shaped frame 246 at which are secured a pair of switches 248 and 249, switch 248 being of the normally open type and 249 being connected normally closed. These switches are operated by depressing plungers 251 and 253, respectively, and are operated only so long as these plungers are held down. The switch 248 is the "Off" switch and such a designation may be imprinted on the top housing member 254 adjacent the diaphragm 255 located above that switch. The switch 249 is the "On" switch and may be so designated on the cover member 254 adjacent diaphragm 255 above that switch. A resilient member 259 formed of spring metal has a central portion secured to the underface of the cover member 254 of chamber 240 by means of the screws 262 and plate 263. The member 259 has one portion 264 carrying button 265 extending under diaphragm 255 with its free end located above the switch button 251. Consequently, downward pressure on the resilient diaphragm 255 depresses button 265 and moves the portion 264 of member 259 downwardly to engage and depress switch button 251 to operate the "Off" switch. The "On" switch 249 is operated in a similar manner by depressing diaphragm 257 against button 267 secured to the left side 269 of member 259.

The pressure control switch 270 is enclosed in housing 271 screwed into the bottom of chamber

240, the housing being open to the pressure in the switch housing 83 through the port 273. The pressure switch is shown in detail in Figure 10, the housing 271 enclosing a diaphragm 275 which diaphragm has its edges secured permanently in place as at 276 by a pressure tight seal. The underface of diaphragm 275 is exposed to pressure in the hose line through the bore 273. The upper face of diaphragm 278 carries an insulating disk 280, the diaphragm being normally held in the position shown in Figure 10, by means of compression spring 282 which bears against the upper face of this insulating disk 280. The insulating disk 280 carries a metallic contact member shown at 283, this member being arcuate in form and extending under the contacts connected to terminals 285 and 286. Consequently, when the pressure in the hose builds up to a predetermined amount it forces the diaphragm 275 upwardly to close the circuit between these contacts and connects terminals 285 and 286 by means of the member 283.

The insulated fluid tight, through connection 288 extends between the interior of chamber 240 and the interior of housing 83 to connect the control line 163 to the switch assembly in the housing.

The switch wiring is shown diagrammatically at the lower left of Figure 5, and shown in plan 30 in Figure 8. The control wire 163 is connected to "Off" switch 248. The opposite side of switch 248 is connected by wire 289 to terminal 286 of pressure switch 270. The same terminal 286 of pressure switch 270 is connected by resistor 353 35 to the "On" switch 249. The other terminal 285 of pressure switch 270 is grounded by wire 290. The other side of the "On" switch 249 is connected to ground by wire 291.

The electronic control enclosed in control 40 housing 157 shown in Figures 1, 2 and 3 is shown diagrammatically, together with associated control lines and switches, in Figure 5. This control is for the operation of the solenoids 145 and 147 shown in Figures 1, 2, 3 and 4 within housing 45 157 and for energizing the meter register engaging mechanism solenoid which is in housing 161 in Figures 1, 2 and 3. The control system in housing 157 of Figures 1, 2 and 3, as shown in Figure 5 includes relays 301 and 303, a transformer 305, 50 a vacuum tube 306, resistors 308 and 309, capacitor 311 and variable resistance 313. The transformer primary 315 is connected to a source of electrical energy (which is here assumed to be alternating current, although direct current 55 could be utilized with only slight modifications) through fuses 317 and 318 and through lines 319 and 320. Application of this electrical energy results in the heating of the filament 322 of the tube 306 to bring said tube to operating condition, since a closed circuit exists from one end of the transformer secondary winding 324 through line 325, filament 322, and ground connection 327 to the other end of the transformer secondary winding 324.

During the positive one-half cycle of the voltage in the secondary winding 329, current flows through line 331, resistor 309, line 333, cathode 335 and plate 336 of the lower half of the tube 306, and line 338. This half of the double triode 70 tube 306 has its grid 340 connected to the plate and is operated as a diode half wave rectifier. During the negative one-half cycle on current flows. Thus a direct current flows through line 331, resistor 309, line 333, the lower half of the tube 306, and line 338. The plate 336 and

the grid 340 are at a positive potential with respect to cathode 335. The cathode 335 is connected to ground. The previously mentioned direct current voltage is applied across resistor 308 and variable resistance 313 causing a direct current to flow from point 342 through variable resistance 313, resistor 308, and the upper half of the tube 306 from grid to cathode 322. The above said current causes a voltage drop across resistor 308, which applies a negative bias on grid 344. Variable resistance 313 regulates the current flow through resistor 308, which in turn regulates the voltage drop across resistor 308, thus regulating the negative bias applied to grid 344.

During the positive one-half cycle of the voltage in the secondary winding 348, current will flow through line 347, through the operating coil of relay 301, the operating coil of relay 303, line 333, the upper part of tube 306, and line 351, provided the negative bias applied to grid 344 is positive enough with respect to the cathode 335 to allow current to flow through the tube between cathode 335 and plate 349. During the negative one-half cycle, no current flows except the discharge current of the capacitor 311, which has a discharge period longer than one-half cycle. This discharge current insures a continuous flow of current, keeping the relays 301 and 303 from chattering.

The variable resistance 313 is adjusted so that the negative bias on grid 344 will prevent the upper portion of the tube 306 from conducting when the "Off" control switch 248 is moved to its "Off" position and also so that the control will operate with the ground return circuit resistance 353 within the limits of predetermined values, when the "On" control switch 249 is moved to its "On" position or the pressure switch 270 shorts out both the resistor 353 and the "On" switch 249.

Pressing the "On" switch button 249 places the control wire 163, resistor 353, and ground return path through wire 86 in parallel with resistor 308 and the tube 306 path from grid 344 to cathode 335, thus reducing the current flow through resistor 308, which lowers the negative bias on grid 344 causing a predetermined amount of current to flow through line 351, transformer secondary winding 348, line 347, operating coil of relay 301 and operating coil of relay 303, and line 333. This amount of current, being insufficient to close relay 303, is of a sufficient amount to close relay 301, the relay 301 being more sensitive than relay 303. Actuating relay 301 closes contacts 302 and causes current to flow through the line 357 from line 319 and from line 357 to line 153 and to the slide valve solenoid coil 145 and through lines 155 and 359 back to line 320, resulting in slow fill. Thus the hose starts to fill.

When the hose has filled with fluid, the pressure switch 270 in the nozzle switch housing 83 shorts out resistor 353, thus decreasing current flow through resistor 308, which decreases the negative bias on grid 344, causing a larger amount of current to flow through line 351, secondary winding 348, line 347, the operating coil of relay 301 and also the operating coil of relay 303, and line 333. This amount of current is sufficient to actuate the relay 303, closing its contacts 364, which causes current to flow through line 357, contacts 302 of relay 301, to actuate solenoid 145 and also contacts 364 of relay 303, line 154 to solenoid coil 147, and line 155 to line 359, thus allowing the full discharge of the pump to enter 75 53 above the return valve 54 which is opened by

the hose. The closing of the contacts 304 of relay 303 also causes current to flow through line 156 to the meter register engaging mechanism solenoid coil 361, in housing 161 and line 160 to line 359. This enables the meter to register the fluid passing through it when the nozzle on the end of the hose is opened and liquid is being discharged.

Pressing the "Off" switch button 248 opens the control wire circuit which returns the current through the resistor 308 to the original value which causes the negative bias on grid 344 of the upper section of tube 306 to go beyond cut-off value, which stops current flow in the upper section of tube 306 from cathode 335 to plate 322, through line 351, transformer secondary winding 348, line 347, operating coil of relay 301 and operating coil of relay 303, and line 333, causing contacts 302 of relay 301 to open, which interrupts current flow through the valve solenoid coils 145 and 147 and meter solenoid 361, causing the valves to be returned to their normal positions so as to evacuate fluid from the hose and to disengage the meter register engaging mechanism.

In Figure 5 there has been indicated the hose 81 and switch housing 83 shown in broken lines. Also the hose reel has been indicated at 381 with the necessary sliding contact between sections of control line 163 indicated at 382. A switch is indicated at 384 which switch may be located on the counter or indicator housing 71 as shown in Figures 1, 2 and 3. This switch may be operated by suitable mechanism so that it will stop the filling operation automatically when a predetermined and preset amount of liquid has passed through the meter. The mechanism for actuating switch 384 forms no part of the present invention and has not been shown. It will be apparent however that opening switch 384, which is normally closed, will have the same effect on the control system as pressing and opening the stop switch 248.

It will be noted that this electronic control has been so designed that the electric energy carried by the control wire in the hose is of such a low level that, when the control wire circuit is broken by any switch or other means, no spark is formed that will ignite gas in a hazardous atmosphere.

The three positions of the valves and control devices are shown in Figures 1, 2 and 3 of the drawings. Figure 1 shows the valves in such a position as to create suction on the hose and evacuate the hose. It will be understood, of course, that the parts are also in this position when the system is used to withdraw gasoline from the tanks on an airplane or from other similar tanks and return the gasoline to the main supply tank.

As shown in Figure 1, the inlet valve 27 is closed and therefore the suction end of the pump 22 is not connected to the main supply tank through pipe 30. The suction intake inlet passage 24 of the pump is, however, connected through pipe passage 32 and through check valve 34 and pipe 35 to valve chamber 37. This valve chamber is open to the common chamber 41 since evacuation valve 39 is raised. The common chamber is connected through dispensing passage 13 to meter 75 and to the hose 81. The discharge valve 43 is closed so that the discharge of the pump through discharge passage 47 cannot enter the common chamber 41. This pump discharge goes through passage 49 to pipe 51 and to chamber 53 above the return valve 54 which is opened by

the pressure. The liquid passes then through passages 56 and 57 to the entrance chamber 29 and back through pipe 30 to the main supply tank.

In order to maintain the various valves in the positions just described, it is to be noted that pressure from the discharge passage 47 goes through perforated control line 59 through passage 61 to cross passage 63 in the slide valve housing 64. Here the pressure passes to the right around slide valve 95 and through pipe 93 to pipe 101 and to the upper portion of chamber 103 above piston 105 to hold the discharge valve 43 closed. Pressure from cross passage 63 also goes around the other slide valve 121 to pipe 119 and into the lower portion of chamber 115 below the piston 117 to open the evacuation valve 39. Further, pressure passes from the right hand slide valve 95 through pipes 93 and 91 to the upper portion of chamber 88 above piston 89 so as to force that piston downwardly closing the inlet valve 27.

It will be noted that under this condition both of the slide valves 95 and 121 are held down by the fluid pressure in the system as neither solenoid 145 or 147 is actuated. Therefore, this is the position which the parts take in the case of control failure when no current is supplied to the control apparatus. This is the safe condition with the hose evacuated and no gasoline being discharged by the equipment.

It is to be noted that under the valve conditions, as shown in Figure 1 and as described above, the opposite sides of the control pistons 105, 117 and 89 are all exposed to suction. Suction passes from suction chamber 37 through passage 66 to the suction chamber 68 in the lower part of the slide valve assembly 64. Suction passes up through the central ports 226 and 227 in the slide valves 95 and 121 and from slide valve 95 through passage 99 and passage 109 to the underside of the piston 105 in chamber 103. It also passes from passage 99 through passage 97 to the underside of piston 89 in chamber 88. In addition, suction passes from slide valve 121 through passage 123 to chamber 115 above piston 117.

As shown in Figure 2, the parts are in position for slow fill. By slow fill is meant a condition under which fluid under pressure is supplied through dispensing passage 73 to meter 75 and hose 81, but a portion of the fluid under pressure is also bypassed to the intake side of the pump. Therefore, because of this by-pass, the supply to the hose is at a substantially lower pressure than if all of the discharge from the pump went directly to the hose. The difference in the adjustment of the several valves from that in which they are shown in Figure 1, is caused by the lifting of the slide valve 95, the slide valve 121 remaining in its lower position. The solenoid 145 is actuated by the electronic control means, shown in Figure 5 and previously described, and lifts the plunger 148 from slide valve 95. The slide valve 95 moves upwardly due to the force of the spring 131. It now serves to connect the cross passage 63 to the opposite passage 99 and the passage 93 previously connected to pressure is now directly opened to the suction chamber 68 in the lower portion of the housing 64. Under these conditions pressure is supplied through passages 61 and 63 to passage 99 from which pressure is supplied through passage 109 to the underside of piston 105 in chamber 103, thus lifting the discharge valve 43. Pressure is also supplied from passage 99 through passage 97 to the underside of

piston 89 in chamber 88 lifting the inlet valve 27. The movement of piston 89 also closes valve 54. The evacuation valve 39 remains open as it did in Figure 1. The position of this valve 39 is controlled by the left hand slide valve 121 which remains in its lower position since solenoid 147 is not operative.

With the valves, as shown in the positions of Figure 2, the fluid delivered under pressure from the pump 22 goes through discharge passage 47 to the common chamber 41 where a portion of it goes through dispensing passage 73 to the meter 75 and hose 81. Since the valve 39 is open, a portion of the fluid under pressure also leaves common chamber 41 through valve opening 40 and passes from chamber 37 through pipe 35 past check valve 34 and through pipe 32 to the suction inlet passage 24 and is recirculated through the pump. Fluid under pressure will also fill passage 49, pipe 51 and enter chamber 53 above valve 54, but its movement is blocked at this point by valve 54 which is closed.

In the position of the valve shown in Figure 3, the solenoid 147 is operated and the plunger 150 lifted from slide valve 121 so that that slide valve is raised to its upper position by spring 133. The other slide valve 95 remains in its upper position in which it is shown in Figure 2. The upper movement of slide valve 121 serves to reverse the flow of pressure and suction to chamber 115 so that there is pressure in the upper portion of this chamber above piston 117 and suction below the piston 117 and the valve 39 is closed. Under these conditions of valve position the fluid under pressure from pump 22 enters the common chamber 41 through the discharge passage 47 and is blocked from movement in any direction except through the dispensing passage 73 leading to the meter 75 and hose 81. Therefore, the fluid under pressure is supplied at full pressure to the discharge hose.

It will be understood from the previous description of the control system shown in Figure 5 that the shift from the evacuation position of Figure 1 to the slow fill position of Figure 2 is accomplished by pressure on the "On" button 249 which serves to actuate solenoid 145. The shift from the slow fill position to the fueling position is automatic and takes place as soon as the hose is full. This is caused by the fuel pressure in the switch housing 83 which actuates the pressure switch 270 which changes the circuit so that solenoid 147 is also actuated.

During the slow fill operation and also during the evacuation operation the solenoid 361 in housing 161 of Figures 1, 2 and 3 is not actuated and the counter or indicator 71 is not connected to the liquid measuring portion of the meter 75. When the solenoid 147 is actuated to bring the system to the fueling position the solenoid 361 is actuated and the counter 71 is clutched to meter 75 and all liquid delivered from the hose is measured and the amount is recorded and indicated. When the hose is evacuated, with the parts as shown in Figure 1, it is not desired to measure the liquid withdrawn from the hose as it was not measured when it was introduced into the hose.

When withdrawing fuel from the tank of a plane or from any other tank through the hose, it may be desired to measure the liquid withdrawn. For this purpose a manual clutch lever 295 is provided by means of which the counter clutch may be operated independently of the solenoid 361 in housing 161.

It will be apparent that the system will always

revert to the evacuation or safe position in the event of control failure. This will happen if control current is interrupted or if the grounding portion 86 of the control wire 163 either purposely or accidentally loses its ground connection to the plane being fueled. This will also happen when the switch 384 is opened by a limiting action when the amount preset on the meter has been delivered. It also happens when the "Stop" button on the switch housing 83 is pressed. If the system fails, it falls in the safe position.

The manual operating valves 136 and 139 can be used to change the valve positions manually, if the automatic control, by means of the solenoids and slide valves fails. It will be apparent that under all conditions shown in Figures 1, 2 and 3, there is pressure on the right side of these valves through pipes 135 and 138. Under all conditions also there is suction on the left side of both valves 136 and 139 through pipe 141 which leads through by-pass passage 32 to the pump inlet passage 24. Consequently, if valve 139 is opened it will transmit suction from the pump intake through line 138 and through the chamber 125 above slide valve 95 through the interior passage 226 in the slide valve to the lower chamber 68. Similarly, pipe 135 is connected to the chamber 126 above slide valve 121, this chamber being in communication with the axial passage 221 through the valve.

With the slide valves 95 and 121 in the lower position shown in Figure 1 there is pressure above both slide valves which, together with the weight of the solenoid plungers and in combination with the suction against the lower faces of the valves keeps the slide valves in this position. If, however, valve 139 is opened then suction is applied to the chamber 125 above valve 95 and this suction, together with the force of spring 131, is sufficient to counteract the weight of the solenoid plunger 148 and lift the slide valve 95 to the position of Figure 2 in which the system is in the slow fill position. This puts the system in the slow fill position as shown in Figure 2.

If the manual valve 136 is also opened the system is moved to the fueling position shown in Figure 3. Suction is applied through pipe 135 to the upper side of the slide valve 121 and that valve is lifted which closes the evacuation valve 39 as described in connection with Figure 3. Thus by the use of manual valves 136 and 139 the system may be operated in the event of failure of the automatic control system for any reason.

While we have shown and described certain preferred valve and control arrangements these are to be understood to be illustrative only as the system is capable of variation to meet differing conditions and requirements and we contemplate such modifications as come within the spirit and scope of the appended claims.

We claim:

1. In a liquid dispensing system, a pump having an inlet passage connected to a source of liquid, a discharge passage connected to the pump, a discharge valve controlling flow through said discharge passage, a common chamber connected to the discharge passage, an evacuation passage connecting the common chamber and the pump inlet passage, an evacuation valve controlling flow from the common chamber to the evacuation passage, a dispensing passage leading from the common chamber, a by-pass passage connecting the discharge side of the pump and the source of liquid, a by-pass valve controlling

flow through the by-pass passage and an inlet valve controlling flow from the source of liquid to the pump inlet passage, suction and pressure operating means for the discharge valve, the evacuation valve, the by-pass valve and the inlet valve, and valve controlled passages for selectively conducting pressure and suction from the pump to said valve operating means.

2. In a liquid dispensing system, a pump having an inlet passage connected to a source of liquid, a discharge passage connected to the pump, a discharge valve controlling flow through said discharge passage, a common chamber connected to the discharge passage, an evacuation passage connecting the common chamber and the pump inlet passage, an evacuation valve controlling flow from the common chamber to the evacuation passage, a dispensing passage leading from the common chamber, a by-pass passage connecting the discharge side of the pump and the source of liquid, a by-pass valve controlling flow through the by-pass passage, an inlet valve controlling flow from the source of liquid to the pump inlet passage, suction and pressure operating means for the discharge valve, the evacuation valve, the by-pass valve and the inlet valve, valve controlled passages for selectively conducting pressure and suction from the pump to said valve operating means and solenoids for operating the valve controls for the passages leading to the valve operating means.

3. In a liquid dispensing system, a pump having an inlet passage connected to a source of liquid, a discharge passage connected to the pump, a discharge valve controlling flow through said discharge passage, a common chamber connected to the discharge passage, an evacuation passage connecting the common chamber and the pump inlet passage, an evacuation valve controlling flow from the common chamber to the evacuation passage, a dispensing passage leading from the common chamber, a by-pass passage connecting the discharge side of the pump and the source of liquid, a by-pass valve controlling flow through the by-pass passage, an inlet valve controlling flow from the source of liquid to the pump inlet passage, suction and pressure operating means for the discharge valve, the evacuation valve, the by-pass valve and the inlet valve, valve controlled passages for selectively conducting pressure and suction from the pump to said valve operating means, solenoids for operating the valve controls for the passages leading to the valve operating means, an electronic system for controlling operation of the solenoids and control switches for the electronic system.

4. In a liquid dispensing system, a source of liquid, a pump connected to the source of liquid, a dispensing hose connected to the pump, a by-pass passage connecting the outlet and inlet sides of the pump, a valve in the by-pass passage whereby the pressure of fluid supplied to the dispensing hose is controlled, electrically controlled means for actuating the valve in the by-pass passage, and a pressure operated switch for operating the electrically controlled means, said switch being responsive to the pressure of liquid transmitted from the pump to the hose.

5. In a liquid dispensing system, a source of liquid, a pump connected to the source of liquid, a dispensing hose and nozzle connected to the pump, a by-pass passage connecting the outlet and inlet sides of the pump whereby the pressure and quantity of the liquid delivered from the pump to the dispensing hose may be reduced,

a by-pass valve controlling the by-pass passage, an electric control system for the by-pass valve, a pressure controlled switch adjacent the nozzle and responsive to fluid pressure in the hose, said switch being connected in the electric control system to close the by-pass valve when said switch is operated by fluid pressure.

6. In a liquid dispensing system, a source of liquid, a pump connected to the source of liquid, a meter connected to the discharge side of the pump, a counter associated with the meter, a clutch for connecting the meter and counter, electric operating means for the clutch, a dispensing hose and nozzle connected to the discharge side of the meter, a by-pass passage connecting the 10 discharged and inlet sides of the pump, a by-pass valve for controlling flow through the by-pass passage, an electrically controlled operating means for the by-pass valve, an electric control system for the counter clutch and the electric by-pass valve operating means, a pressure switch responsive to fluid pressure in the hose, said switch being connected in the electric control system to close the clutch to connect the counter to the meter and to close the by-pass 15 valve when pressure in the hose reaches a predetermined amount.

7. In a liquid dispensing system, a liquid pump, a meter connected to the discharge side of the pump, a counter associated with the meter, a 20 clutch for selectively connecting the meter to the counter, an electric control for actuating the clutch, said clutch being normally disconnected, a pressure operated switch adapted to be closed by a predetermined fluid pressure in the hose, 25 said switch being connected in the clutch control circuit to operate the clutch to connect the counter to the meter when the switch is closed.

8. In a liquid dispensing system, a liquid pump, a meter connected to the discharge side of the pump, a counter associated with the meter, a clutch for selectively connecting the meter to the counter, an electric control for actuating the clutch, said clutch being normally disconnected, a pressure operated switch adapted to be closed by a predetermined fluid pressure in the hose, said switch being connected in the clutch control circuit to operate the clutch to connect the counter to the meter when the switch is closed and manual means for actuating the clutch independently of the electric control.

9. In combination with a liquid dispensing system including a pump, a dispensing hose, passages connecting the pump inlet and outlet and the hose, and valves controlling said passages whereby liquid may be selectively supplied to the hose at low and high pressure and withdrawn from the hose, an electronic control system for

said valves, said system comprising solenoids for controlling the valves, relays for controlling the solenoids, an electronic tube having a plate, grid, and cathode, the relays being connected in the plate circuit, and switch controlled circuits for varying the grid bias to control relay operation, one of said circuits shifting the liquid supply to said hose from low to high pressure, the switch for said circuit being associated with the hose and actuated by low pressure liquid in the hose, a meter connected between the pump and hose, a counter associated with the meter, a clutch for connecting the counter to the meter, a solenoid for actuating the clutch, and a relay for controlling the solenoid, the relay being connected in the circuit for shifting the liquid supply to the hose from low to high pressure whereby the clutch is actuated to connect the counter to the meter when the pressure is shifted to high.

10. In combination with a liquid dispensing system, including a pump, a meter connected to the discharge side of the pump, a counter associated with the meter, a clutch for connecting the counter to the meter, a dispensing hose connected to the outlet side of the meter, liquid passages connected to the pump outlet and inlet sides, valves controlling flow through said passages whereby the pump will selectively deliver liquid at high or low pressure or withdraw liquid from the meter and hose, said valves being normally in position to withdraw liquid from the meter, solenoids for actuating the valves and for actuating the clutch to connect the counter to the meter, relay controlled circuits for actuating the solenoids, an electronic circuit including a tube having a plate, grid and cathode, the relays being connected in parallel in the plate circuit, and switch controlled circuits for varying the grid bias to control relay operation, one relay operating the solenoid to cause low pressure discharge under certain bias conditions and said relay and a second relay controlling high pressure flow and counter clutch solenoids both operating under different bias conditions.
